(57) **CLAIM**

The ornamental design for a pipe saddle with hanger retainer, as shown and described.

DESCRIPTION

FIG. 1 is a perspective of a pipe saddle with hanger retainer showing our new design;

FIG. 2 is a front elevation view of the pipe saddle with hanger retainer;

FIG. 3 is a right elevation view of the pipe saddle with hanger retainer;

FIG. 4 is a bottom plan view of the pipe saddle with hanger retainer;

FIG. 5 is a rear elevation view of the pipe saddle with hanger retainer; and,

(Continued)

FIG. 6 is a left elevation view of the pipe saddle with hanger retainer.

The broken lines show portions of the design that form no part of the claimed design.

1 Claim, 6 Drawing Sheets
